UNITED STATES PATENT OFFICE.

CALVIN ALEXANDER ELY, OF TAYLOR HILL, ILLINOIS.

RAILWAY-GATE.

SPECIFICATION forming part of Letters Patent No. 289,244, dated November 27, 1883.

Application filed June 14, 1883. (No model.)

To all whom it may concern:

Be it known that I, CALVIN A. ELY, of Taylor Hill, in the county of Franklin and State of Illinois, have invented certain new and useful Improvements in Railway-Gates; and I do hereby declare the following to be a full, clear, and exact description of the invention, such as will enable others skilled in the art to which it pertains to make and use it, reference being had to the accompanying drawings, which form part of this specification.

My invention relates to an improvement in railway-gates; and it consists in the peculiar combination and arrangement of devices to be more fully set forth hereinafter, and particularly pointed out in the claims.

In the drawings, Figure 1 is a top plan view. Fig. 2 is a side elevation. Fig. 3 is a vertical longitudinal section. Figs. 4 and 5 are detailed vertical cross-sections on the lines S S and X X of Fig. 1. Fig. 6 is a vertical cross-section, representing a supplemental gate-bar that may be employed.

A represents a gate, which is composed of a shaft, B, and rods D, secured at their lower ends in the shaft B, and extending upward from it at right angles to its length. The shaft B is journaled in bearings C, that are secured beneath the track-rails, the shaft being by this arrangement allowed to turn through half a circle. In order to keep the rods D normally vertical, I provide the weights E, which are secured to depending ends D' of the rods D, as shown; or suitable springs may be employed for this purpose, if so preferred.

F F represent operating-rails, which are secured in position on the inner sides of the track-rails and extend in opposite directions, and are allowed a slight lateral play. In order to provide for this lateral movement, I employ slightly curved rods G S, which have their ends bent downward at right angles, which bent ends G' S' enter the cross-ties, while the intermediate portions, G² S², extend through openings F' made in the rails. Extensile springs R are employed upon the rods S, in order to keep the rails F normally pressed against and in contact with the inner sides of the track-rails. This construction of parts is shown in detail at Figs. 4 and 5.

H H represent bell-crank levers, which le-

vers are pivoted to plates secured to the cross-ties at the points I, and have the springs N bearing against them, the function of these springs N being to keep the levers normally 55 in the position shown in solid lines throughout the various figures. The inner ends, H', of the arms H are bent up at right angles and bear against the inner sides of the rails F, while the outer ends of these levers have pivoted in them the rods K, which rods are confined in place by the keepers L, secured in the cross-ties, and allowed a longitudinal movement. The free ends of the rods K are bent down under the shaft B, as at K', and are provided with tappet enlargements M, which enlargements strike against the depending ends 60 D' of the gate-rods D, when one of the rails F is moved inward by the flanges of the wheel of an advancing train, and thus causes the 70 gate to be tilted and allow the train to pass over it.

It is necessary, in order to keep the gate tilted during the passage of the train over it, that the inward movement of the first rail 75 F, with which the wheels of the advancing train come in contact, should be communicated to the oppositely-extended rail F, and that both of them should assume and retain the same position. In order to accomplish this, 80 I provide a bearing-plate, V, secured to the two central ties, W W, a lever, O, pivoted centrally on the plate V, and the connecting-rods P. These rods P are pivoted at their outer ends to the outer ends of the lever O and 85 at their inner ends to the projecting lugs T, which extend from the inner sides of the rails F. These lugs T, when the gate is tilted, extend into the paths of and over the rods D of the gate, which are adjacent to the inner sides 90 of the track-rails, and lock the gate in that position, as shown at Figs. 1 and 3 in dotted lines, and thus prevent the possibility of the gate springing into an upright position during the passage of a train over it. When the 95 last wheel of the passing train leaves the outer end of the rail F, extending in the direction in which the train is moving, both rails move outwardly against the inner sides of the track-rails by reason of the springs R, as previously 100 described. The lugs T are moved out of the way of the gate-bars D, which they confined

while the train was passing, and the weights E cause the gate to assume its normal vertical position.

In Fig. 6 I illustrate a mode of construction 5 that may be employed in order to prevent too great a space from being left between the bars of the gate at the points through which the rails of the track and the operating mechanism pass.

10 Z represents a bar, which is pivoted at its lower end to the inner side of the rail F, at a point immediately above the shaft B, and which has its upper end bent at right angles and provided with the long slot Y. Through 15 this slot Y extends the upper portion of the rod D, adjacent to the said rail F. When the gate is tilted, the supplemental bars Z are tilted with it, as will be readily understood. Transverse braces may also be employed on 20 the gate, if desired.

I do not desire to limit myself to the precise construction hereinbefore described, as it is obvious that many modifications may be made therein without departing from the 25 spirit of my invention. For instance, I may dispense with one of the rails F and the connecting mechanism P O, and employ only one operating-rail, which should be long enough to extend a suitable distance on the track on 30 both sides of the gate. When thus modified two or more securing-rods, S, and bearing-springs R, will be preferably employed in connection with the operating-rail.

Having thus described my invention, I 35 claim—

1. The combination of a pivoted gate mechanism for keeping it normally vertical, operating-rails secured normally against the track-rails, and provided with projecting locking-lugs, mechanism for securing the operating-rails in place and allowing lateral movement thereof, and mechanism for connecting the 40

rails, with the gate whereby, when the rails are moved laterally, the gate will be tilted and locked in position, substantially as shown. 45

2. The combination of an operating-rail, F, securing rod or rods S, bearing spring or springs R, lever H, connecting-rod K, and pivoted gate A, provided with mechanism for keeping said gate normally vertical, substantially as described. 50

3. In a railroad-gate, the combination of an operating-rail, F, having locking lug or lugs T, securing rod or rods S, bearing spring or springs R, lever H, connecting-rod K, and pivoted gate A, provided with mechanism for keeping said gate normally vertical, substantially as specified. 55

4. In a railroad-gate, the combination of the operating-rails F, pivoted connecting-lever O, and rods P, securing-rods S, bearing-springs R, levers H, connecting-rods K, and pivoted gate A, provided with mechanism for keeping it normally vertical, substantially as set forth. 60

5. In a railroad-gate, the combination of the operating-rails F, having locking lugs or projections T, pivoted connecting-lever O, and rods P, securing-rods S, bearing-springs R, levers H, connecting-rods K, and pivoted gate 70 A, provided with mechanism for keeping it normally vertical, substantially as described. 75

6. In a railroad-gate, the supplemental bars Z, pivoted to the operating-rails at their lower ends, and having their upper ends secured in any suitable manner to the adjacent bars of the gate, substantially as hereinbefore set forth.

In testimony whereof I affix my signature in presence of two witnesses.

CALVIN ALEXANDER ELY.
